SELF CLEANING PHONOGRAPH NEEDLE

Filed Nov. 10, 1930

CHARLES W. HALL

By *R. Hallmark* Attorney

UNITED STATES PATENT OFFICE

CHARLES W. HALL, OF DENVER, COLORADO, ASSIGNOR OF ONE-HALF TO MALCOLM S. LOSEY

SELF-CLEANING PHONOGRAPH NEEDLE

Application filed November 10, 1930. Serial No. 494,470.

This invention relates to a phonograph needle and has for its principal object the provision of a phonograph needle which will simultaneously clean the record grooves while it is playing.

Another object of the invention is to provide a self-dampening phonograph needle, that is, one in which will be incorporated means for dampening or cushioning the vibration of the needle so as to soften the tone of the reproduction.

A further object is to effectively combine the cleaning and dampening features as an integral part of the needle so that whenever the needle is changed the cleaning and dampening medium will also be changed, and so that it will be unnecessary to apply any attachments to the reproducer or tone arm.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 illustrates the invention in use upon a phonograph.

Fig. 2 is a greatly magnified side elevation of the improved phonograph needle.

Fig. 3 is a similarly magnified plan view thereof.

Fig. 4 is a perspective view illustrating the actual size of the needle.

Figs. 5 and 6 illustrate alternate methods of constructing the improved needle.

In Fig. 1 typical parts of a phonograph are designated by numeral as follows: turn table 10; record 11; reproducer 12; needle arm 13; needle arm set screw 14; and tone arm 15.

In its simplest form the invention comprises a needle 16, which may be of any of the usual types of replaceable phonograph needles, preferably having a tapered point

or extremity for engagement in the grooves of the record 11. Suitable adhesive is applied to the point or tapered portion of the needle 16. The point is then forced through a collar or pad 17 of soft yieldable material so that the pad is securely cemented to the needle with the needle point slightly projecting therethrough as indicated in Fig. 2.

The pad 17 may be of any desired shape or material. It is preferably formed by stamping a circular collar from relatively thick felt. Felt having a thickness of approximately one-eighth of an inch has been found to be very satisfactory.

The needle 16 is placed in the needle arm 13 of the phonograph similarly to the ordinary needle and is clamped therein by the needle arm set screw 14. The natural angular position of the needle arm 13 causes one edge of the pad 17 to be forced against the record 11 immediately ahead of the needle as shown in Fig. 1. As the turn table 10 rotates the record grooves must pass under the contacting pad 17 before reaching the needle 16 so that the grooves are scoured or cleaned before contacting with the needle point. This cleaning action greatly increases the life of the record and needle since no abrasive substances remain in the grooves of the record to cause wear.

By having the pad 17 circular the needle can be placed in the needle arm in any position and will always uniformly contact with the record. The needle can be rotated to bring a fresh portion into contact with the record should one side thereof become soiled. The needles are comparatively inexpensive to manufacture so that they can be discarded should the pads become unduly dirty or should the needle become worn.

In addition to the self cleaning feature of the pad 17 it has been found that it also serves an additional function in that it acts to dampen or cushion the vibrations of the needle so as to remove discordant rattling, scratching or tinpanny sounds from the final tone.

The pad 17 can be applied to the needle in any desired way. The above described method has been found to be very satisfactory.

6 A second method, however, is illustrated in Fig. 5 in which a backing 18 of relatively stiff material such as card board is employed to hold a felt pad 19 in place. The needle is forced through the backing 18 which frictionally engages the tapered portion thereof to prevent the pad 19 from being forced upwardly on the needle. In this form no adhesive or cement is required.

10 In Fig. 6 still another method of applying the felt or yieldable pad is illustrated. In this method a needle 20 is formed with a shoulder 21 adjacent its point. The shoulder 21 acts to prevent a pad 22 from being forced upwardly on the needle without the use of adhesive or cement. All of the forms operate similarly when in place in the needle arm of a phonograph.

15 It has been found very desirable, although not necessary, to have the pads slightly dampened with oil. This serves a double purpose. First, it lubricates the record so as to lessen the friction and resultant noise, and second, it causes dust and other foreign 20 material to be more readily removed and to adhere more tenaciously to the pad.

25 While a specific form of the improvement has been described and illustrated herein, it is desired to be understood that the same may 30 be varied, within the scope of the appended 90 claims without departing from the spirit of the invention.

Having thus described the invention, what 35 is claimed and desired secured by Letters 160 Patent is:—

40 1. A phonograph needle comprising: a needle member; and a yieldable pad carried by said needle member and adapted to contact with the phonograph record while said 105 needle member is in contact therewith.

45 2. A needle for playing phonograph records comprising: a pointed needle member; a collar of yieldable material surrounding said needle member adjacent its point so that 110 said collar will contact with said record when said point is in contact therewith.

50 3. A needle for playing phonograph records comprising: a pointed needle member; a collar of yieldable material surrounding 115 said needle member adjacent its point so that said collar will contact with said record when said point is in contact therewith; and means for preventing said pad from being forced upwardly on said needle away from the point thereof.

55 4. The combination with a pointed phonograph needle of a pad of yieldable material attached thereto adjacent the point thereof.

60 5. The combination with a pointed phonograph needle of a felt pad surrounding the point of said needle and adapted to contact 120 with a phonograph record while said point is in contact therewith.

65 6. The combination with a phonograph 130 needle of a collar surrounding and extending

70 outwardly from said needle, and a pad of yieldable material positioned against said collar so as to contact with a phonograph record while said needle is in contact therewith.

7. The combination with a pointed phonograph needle of a pad of yieldable material attached thereto adjacent the point thereof, said pad being moistened with an oil.

75 In testimony whereof, I affix my signature.

CHARLES W. HALL.
